DESIGN FOR A BOX FOR BOTTLE OR
SIMILAR ARTICLE

Georges Baud, Paris, France

Application May 8, 1946, Serial No. 129,439

Term of patent 14 years

(Cl. D58—11)

To all whom it may concern:

Be it known that I, Georges Baud, a citizen of the Republic of France, residing at Paris, France, have invented a new, original, and ornamental Design for Box for Bottle or Similar Article, of which the following is a specification, reference being had to the accompanying drawing, forming part thereof, in which the figure is a perspective view of the box showing my new design.

I claim:

The ornamental design for a box for bottle or similar article, substantially as shown.
